(57) **CLAIM**

The ornamental design for a gate stop, as shown and described.

DESCRIPTION

FIG. 1 is a top, front, and right side perspective view of a gate stop according to my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.
The dot-dash broken lines represent boundaries of the claimed design and form no part of the claimed design. The dash-dash broken lines depict portions of the gate stop that form no part of the claimed design.

1 Claim, 6 Drawing Sheets
